SAFETY RAZOR

Axel S. Carlson, New York, N. Y., assignor of
one-half to Concetta L. Blue, Brooklyn, N. Y.

Application November 27, 1934, Serial No. 754,969

12 Claims. (Cl. 30—61)

My invention relates to a type of safety razor in which there is a fixed support and a hinged clamping plate between which the razor blade may be clamped and held. Such type is illustrated in my patent application for Safety Razor Holder, filed October 15, 1934, Serial No. 748,371, matured into Patent No. 2,024,626, dated Dec. 17, 1935.

My invention also embodies the feature of the clamping plate being turned on its hinge by a rack and pinion and the pressure for clamping the blades is done by a stem which rotates through a quarter turn to engage and free the hinged clamping plate. Such construction pertains to a type set forth in my patent application for Hinged Clamp Safety Razor Holder, filed January 3, 1934, Serial No. 705,081, matured into Patent No. 2,008,681 dated July 23, 1935.

One of the main objects and features of my present invention is that the clamping plate may be rotated on its hinge by the operator moving such clamping plate with the fingers independently of a movement of the rack developed by a longitudinally movable stem and a wedge block. This is accomplished by having a lost motion between the rack and the wedge block due to the employment of a spring which bears on one portion of the rack bar and at its opposite end engages a floating abutment block which contacts the stem and the wedge block which reciprocates with the stem. Therefore, in opening the clamping plate this can be tilted upwardly after rotating the stem one quarter turn to loosen the head and then the movement of the rack allows an extension of the spring, the spring urging the rack bar in its movement of opening the clamping plate. In the movement of closing the clamping plate to engage a blade the rack bar compresses the spring but this may be done without a positive wedging movement of the wedge block.

Another object and feature of my invention is in giving a positive one quarter turn to the stem to turn the head of such stem and this is done by having an L-shaped guide groove cut in a sleeve, the sleeve being inserted in the handle of the razor, and the stem is provided with a pin which engages in this slot. One arm of the slot extends longitudinally of the sleeve and the other arm circumferentially. Therefore, it is necessary when the head is in clamping position and in the circumferential slot to give the stem a quarter turn before the pin can travel in the longitudinal arm of the slot. This accommodates both the rotational and the longitudinal movement of the

head of the stem to release the clamping plate to permit its hinging movement.

Another feature of my invention relates to the construction for giving a tension on the stem to tightly engage the clamping plate and thus hold the blade in operative position. In this construction I use a rotatable knob which is threaded in the handle of the razor, preferably by fine, left hand threads, and in this knob the stem is threaded, using coarse pitch threads, preferably right hand, and in order to maintain a positive friction of the coarse threads a compression spring in the base of the knob always exerts a pressure on the end of the stem. Thus, by rotating the knob an initial action to loosen the pressure of the head on the clamping plate may be obtained and then, due to the friction action of the coarse threaded stem the stem may be turned a quarter turn and then moved longitudinally when the pin on the stem engages in the longitudinal section of the slot of the sleeve.

A further detailed feature of my invention relates to a type of slip construction in connecting the arms of the clamping plate to accommodate blades of different thickness. And another detailed feature relates to a stop limit on the arm of the clamping plate which limits the movement of this to an open position and this prevents an operator breaking any of the parts of the razor in opening and closing the clamping plate by hand.

Another feature is in the construction of the blade and its mounting, the blade being double-edged, provided with a longitudinal slot with a central enlarged opening through which the stem extends and with two guide slots adjacent each cutting edge through which guide plates or dowels extend. The opposite ends of the blade have tongues which extend through openings or notches formed in the end structure of the supporting plate of the razor. Thus, by engaging these tongues the blades may be readily inserted in or removed from the supporting plate.

My invention is illustrated in connection with the accompanying drawings, in which:

Fig. 1 is a side elevation with a handle partly broken away showing the razor in its closed and operative position with the stem head in the clamping position.

Fig. 2 is an elevation similar to Fig. 1 but with the clamping plate in its open position, the stem head being rotated and the stem elevated.

Fig. 3 is a section on the line 3—3 of Fig. 2 in the direction of the arrows, the hinge construction of the clamping plate being omitted.

Fig. 4 is a section similar to Fig. 3 with the blade removed and showing the upper surface of the clamping plate.

Fig. 5 is a longitudinal section through the handle, the supporting and clamping plates, with the clamping plate in the open position; this section may be considered as taken on the line 5—5 of Fig. 6 with the clamping plate open.

Fig. 6 is an end elevation taken on the arrow 10 6 of Fig. 1 illustrating part of the hinge.

Fig. 7 is a transverse section on the line 7—7 of Fig. 1 in the direction of the arrows.

Fig. 8 is a plan taken in the direction of the arrow 8 of Fig. 1 with the razor in operative position.

Fig. 9 is a detail perspective of the wedge block on the stem.

Fig. 10 is a detail perspective of the guide sleeve.

In my invention I employ a tubular handle 11, to which is connected a supporting plate 12 and 20 hinged to one end of the supporting plate there is a clamping plate 13. These plates clamp the blade 14 in position for shaving.

The stem, designated 15, has a lower section 16 with coarse screw threads 17 thereon, these being preferably right hand. The stem has a restricted neck 18 made by having a tongue 19 which is inserted in a socket 20 in the upper end of the section 16. This end is held by a pin 21 (note Fig. 5). Thus there is a shoulder 22 on the end 30 16 and a shoulder 23 at the other end of the neck. The upper end portion 24 of the stem extends through a perforation 25 in the clamping plate and has a head 26 at its upper end. This head is formed oblong in shape, the long measurement 35 27 (note Fig. 6) being greater than the width of the slot 28 (note Fig. 8) in the clamping plate through which the stem extends. The narrow measurement of the head is less than the width of the slot 28 to allow the head when turned to 40 pass through this slot in the manner hereinunder detailed.

The threaded end 17 of the stem is threaded with coarse threads 30 in the knob 31. This knob has a fine threaded section 32 engaging the internal threads on the lower end of the tubular handle. These threads are preferably left hand. The outside of the knob is knurled as indicated at 33. In axial alignment with the threads 30 there is a compression spring 34 which bears on 45 the bottom of the threaded socket 35 in the knob and this compression spring always maintains a friction action between the coarse threads 17 of the stem and the coarse threads 30 of the knob.

A guide sleeve 40 is secured in the upper portion 50 of the handle and this has an L-shaped guide slot 41 therein, the slot having a longitudinal arm 42 and a circumferential arm 43 (note Figs. 1 and 10), the pin 21 on the stem extending into this L-shaped slot. The circumferential arm 43 is 55 wider in a longitudinal direction than the diameter of the pin 21 to permit a longitudinal movement of the stem when the pin is engaged at the portion 43 of the slot 41.

A rivet 44 through the sleeve and the tubular handle 11 retains the sleeve in position. The sleeve also has longitudinal slots 45 which engage splines 46 on a wedge block 47. This block is 60 rotatably mounted on the neck portion 19 of the stem between the shoulders 22 and 23 and has a wedging head 48 at its upper end with a wedge-shaped surface 49 on one side and a non-wedging parallel bearing face 50 on the other side (note Fig. 9).

The hinge construction is as follows: The base 75 55 of the supporting plate 12 has a pair of de-

pending ears 56 (note Fig. 6), these being located at one end. Through these ears extends the hinge pintle 57, this having a pinion 58 at the center and flattened end strips 59. The main block 60 of the clamping plate is provided with a pair of arms 61 at right angles thereto and these arms each have a longitudinal slot 62 through which extends the flattened end 59 of the pintle. The slot is longer than the flattened end so that when the clamping plate is in the clamped position of 10 Fig. 1 it may have a slight movement in the axial direction of the handle to accommodate thick or thin blades and to permit the clamping action.

One of the arms has a stop finger 63 which, when the clamping plate is in the open position of 15 Fig. 2, engages the under side of the supporting plate and thus limits the opening movement.

The pinion 58 is rotated by movement of the rack bar designated by the assembly numeral 65. This has a thick section 66 which slides in guides 20 on the under surface of the base 55 of the supporting plate and operates through slots 67 in the upper end of the handle. The rear end of the rack bar has a wedge 68 which co-acts with the wedge surface 49 of the wedge block. A reduced 25 end 69 of the rack bar has rack teeth 70 engaging the pinion 58 and guides between the ears 56. The rack bar has a hollowed space 71 and perforations 72 at the end of this space and in these perforations slides the floating abutment block 73, 30 this having a rounded end 74 (note Fig. 5) to engage the longitudinal non-wedging surface 50 of the wedge block. Attached to the abutment block there is a guide rod 75, which has its end operating in a guide socket 76 in the thick section 35 of the rack bar. A compression spring 77 is coiled on this rod and bears against abutment surface 78 at the end of the space 71 and on the shoulder 79 on the abutment block 73.

The blade 14 has parallel cutting edges 85 and 40 tongues 86 at each end. From the tongues there are right angular ends 87. The center of the blade is provided with a slot 88 extending longitudinally, this slot having a central enlargement 89 to accommodate the upper portion 24 of the 45 stem. A pair of short parallel slots 90 accommodate the guide pins 91 secured to the supporting plate 12.

The features of the supporting plate to accommodate the blade are transverse ribs 92 which 50 terminate at 93 outside of the marginal edges 94 of the supporting plate 12. Extending upwardly from each rib there is a thin fin 95 on which the blade is supported. This construction leaves a series of depressions 96 between the ribs and the 55 fins. A comb or guard 97 has teeth 98 (note Fig. 7) which are molded in the body structure of the supporting plate and curve upwardly in alignment with the ribs 92. These teeth extend beyond the edge 94 of the supporting plate 12. At each end 60 of the supporting plate there are upwardly extending shoulders 99 with a space 100 therebetween. Such space accommodates the tongues 86 of the blade and the shoulders 99 engage the ends 87 of the blade. Thus the blade is held from 65 longitudinal movement on the supporting plate. The cutting edges of the blade extend beyond fins 95 and thus overlap the comb or guard teeth 98.

The clamping plate has a series of transverse ribs 101 which have lateral extensions 102 which extend slightly beyond the marginal edges 103 of the clamping plate (note Fig. 8). The ribs 101, when the blade is clamped, align with the ribs 92 and fins 95 on the supporting plate.

The manner of operation and functioning of my invention is as follows:

Presuming the clamping plate is in the open position of Fig. 2, then the fingers 63 on the arm 61 engage the under side of the supporting plate and prevent further opening movement of this clamping plate. A blade may then be inserted on the supporting plate 12. In this position the wedge block 47 is in its uppermost position, as shown in Figs. 2 and 5, and the rack bar is moved to its extreme position to the right, having reference to these figures. The head of the stem is also positioned longitudinally of the slot 28 so that the blade may be readily inserted over its head and in the closing movement of the clamping plate the head passes through the slot in such clamping plate. The clamping plate may then be manually rotated by engagement with the fingers until it occupies the position shown in Fig. 1, in which case the rack bar 65 will be moved to the left but as no movement yet has been given to the wedge block the spring 71 becomes compressed. In order to clamp the blade it is necessary to lower the head 26 on the stem. This is done by rotating the knob 31. On account of the coarse threads 17 on the stem the pin 21 is lowered in the longitudinal branch 42 of the L-shaped slot 41. Then when this pin aligns with the circumferential arm 43 of this slot the pin 21 may be shifted to one side, thus rotating the stem a quarter turn. The continued rotation of the knob 31 by the threading action in the threads 32 exerts a tension or pull on the stem, thus bringing pressure to bear on the upper surface of the clamping plate and thereby securely holding the blade between the two plates 12 and 13.

In this action of lowering the stem the wedge block 46 has been lowered, the stem being free to rotate in this block, the block being guided in a rectilinear motion. The block, if desired, may be lowered until its wedge 49 is completely below the wedging portion 68 of the rack bar. However, if the clamping plate has not been swung on its hinge by the operator it may be moved by the rotation of the knob 31, in which case the wedging portion 48 of the wedge block 47 acts on the wedging portion 68 of the rack bar and moves this rack bar to the left, (with reference to Fig. 5), which action rotates the pinion 58 and thus swings the clamping plate 13 on its hinge. When the head 26 of the stem engages the upper surface of the clamping plate it may cause a slight movement of pintle ends 59 in the slot 62 to accommodate blades of different thicknesses and to afford a tight clamping action.

In order to open the clamping plate 13 from the closed position of Fig. 1 it is necessary to rotate the knob 31 in a reverse direction to that above described. The first action of this is to relieve the pressure between the head 26 and the clamping plate. The next action, on account of the friction between the screw 17 and the knob, is to rotate the pin 21 with the stem a quarter turn to bring this pin into alignment with the longitudinal portion 42 of the L-shaped slot 41. A further rotation of the knob elevates the pin 21 and thus raises the knob 26 which has been rotated to align with the slot 28.

As soon as the head or knob 26 on the end of the stem has been aligned with the slot 28 in the clamping plate 13 this plate may be raised by hand, which action, on account of the constant mesh of the pinion 58 and the rack 70, will tend to move the rack bar 65 to the right, having reference to Fig. 5, but such rack bar

cannot be moved its full distance until the wedge block 47 has been moved upwardly on account of the contact between the wedging portion 48 of the block and the wedging end 68 of the rack. The wedging block is elevated by rotating the knob 31 in a left hand direction if it has left hand threads, this being in the direction of the arrow 105 of Fig. 1, which turns the stem 15 in the reverse direction of the arrow 106 of Fig. 1. In this movement the floating abutment block 73 rides from the position in which it rests on the upper portion 24 of the stem as shown in Fig. 1 to the position resting on the surface 50 of the wedging block. Instead of raising the clamping plate 13 by the fingers this may be done entirely by rotation of the knob 31 in the manner above described, in which case the reaction of the compression spring 71 thrusts the rack bar 65 to the right, having reference to Fig. 5, and this opens the clamping plate to the position of Fig. 5, that is, until the finger 63 on the arm 61 contacts with the under side of the supporting plate 12 and the wedging portion 48 of the wedge block. But, manifestly, it is necessary to first relieve the pressure of the head 26 of the stem on the clamping plate and then rotate this head into alignment with the slot 28.

It will, therefore, be seen that the clamping plate 13 may be moved from an open to a closed position by manually swinging this on its hinge and then subsequently while it is held in its closed position moving the wedge block and the head of the stem by rotating the knob 31 in an unscrewing action as regards the handle. But before the clamping plate can be opened, that is, from its clamped to its open position, the head 26 of the stem must be turned one-quarter turn to align with the stem 28. The wedge block must be moved to its upper position.

The compression spring 71, thus, on account of its resiliency, gives a smooth and a quick action to the opening of the clamping plate. The arrow 106, (Fig. 1) indicates the direction of rotation of the stem 105 when the pin 21 is moved horizontally in the transverse arm 43 of the slot 41 from its position when in alignment with the longitudinal arm 42 of the slot.

The guide block 47 is provided with a side surface 49' parallel to the stem, this being above the wedge surface portion 49. This engages a complementary surface 68' at the upper part of the wedge portion 68 of the rack bar 65. This prevents the clamping plate from rising under the influence of the spring 71 before the stem has been given a full one-quarter turn, for when the wedge block 47 is lowered the edge 49' contacts with the lower corner of the wedge portion 68 of the rack bar.

Various changes may be made in the details of construction without departing from the spirit or scope of my invention as claimed in the appended claims.

I claim:

1. In a safety razor having a handle, a supporting plate connected thereto, a clamping plate hinged to the supporting plate and having a pinion on the hinge, a rack bar slidably mounted on the supporting plate, a stem extending through the handle and having an elongated head on the end, the clamping plate having a slot through which the head may pass, the head being longer than the width of the slot, a spring, said rack being operative on movement of the clamping plate from its open to its closed position by en-

gaging such plate to compress the spring, means in the handle to longitudinally move the head of the stem and to rotate the stem to clamp said clamping plate in its operative closed position.

5. 2. In a safety razor as claimed in claim 1, a wedge block mounted on the stem, an interacting means between the wedge block and the rack to positively move the rack to swing the clamping plate from its open to its closed position independently of this plate being moved by hand, the movement of the wedge block and stem in the opposite direction being adapted to free the rack for an opening movement, and said spring urging said rack in its movement to swing the 10 clamping plate from its closed to its open position.

3. In a safety razor having a supporting plate, a handle connected thereto at right angles, a clamping plate having arms, a hinged connection 20 between the arms and the supporting plate having a pinion, a rack bar slidably mounted on the supporting plate having teeth meshing with the pinion, said rack having a hollow space, the supporting plate having a perforation and the 25 clamping plate having a long slot, a stem extending through said perforation and slot, said stem having a head of greater length than the width of the slot, means to operate said stem to rotate the stem a quarter turn and to move 30 the stem longitudinally to engage the clamping plate by said head, a spring mounted in the hollow space of the rack and compressible against the stem in moving the clamping plate from its open to its closed position.

35. 4. In a safety razor as claimed in claim 3, the stem having a rack bar engaging means rotatably mounted on said stem and longitudinally movable with said stem, the rack bar having a complementary engaging means whereby a longitudinal movement of the stem and its engaging means in one direction operates to positively shift the rack bar to swing the clamping plate from its open to its closed position, but the movement 40 of the stem in the opposite direction being inoperative to positively move the rack bar.

5. In a safety razor as claimed in claim 3, said spring being adapted, after a longitudinal and rotating movement of the stem, to release the clamping plate to shift the rack bar and hence 50 actuate the pinion to swing the clamping plate from its closed to its open position.

6. In a safety razor as claimed in claim 3, a guide means to effect rotation of the stem comprising a structure having an L-shaped slot connected to the handle, one arm of the slot being longitudinal and the other arm circumferential, and a pin secured to the stem operating in said slot.

7. In a safety razor as claimed in claim 3, the 60 means to move the stem comprising a knob having a threaded connection to the handle by fine threads, the stem being threaded in the knob with coarse pitch threads, the threads between the knob and the handle and the threads between the stem and the knob being inclined at an opposite direction.

8. In a safety razor having a supporting plate, a tubular handle connected thereto, a clamping plate having arms, a hinged connection between 70 said arms and the supporting plate including a pintle having a pinion, a rack bar slidably mounted on the supporting plate and operating through slots in the handle, said rack bar having rack

teeth engaging the pinion and having a hollow space, an abutment block having a guide rod operating in a guide socket in the rack bar, a coiled compression spring bearing against one portion of the rack bar and the abutment block, the supporting plate having a perforation, the clamping plate having an elongated slot, a longitudinally moveable stem in the handle extending through the perforation in the supporting plate and having a head to pass through the slot of the clamping plate, the head being longer than the width of the slot, a knob rotatably mounted on the end of the handle, an interconnection between the knob and the stem to longitudinally move the stem on rotation of the knob, a positive guide means operating between the handle and the stem to rotate the stem a quarter turn on its longitudinal movement, the abutment block being adapted to engage the stem whereby on movement of the clamping plate from its open to its 10 closed position said spring is compressed.

9. In a safety razor as claimed in claim 8, an interconnecting means between the stem and the rack bar to rotate the pinion and swing the clamping plate from its open to its closed position, said spring being operative on release of the 15 clamping plate by the head of the stem to move the rack bar and thereby rotate the pinion to swing the clamping plate from its closed to its 20 open position.

10. In a safety razor as claimed in claim 8, the rotatable connection of the knob to the handle comprising threads of fine pitch between the handle and the knob, the stem and the knob having a threaded connection with coarse threads, a 25 spring in the knob bearing against the end of the stem, the threads between the knob and the handle and between the knob and the stem being inclined in opposite directions.

11. In a safety razor having a supporting plate having a perforation, a clamping plate having a slot, a stem extending through said perforation and having a head to extend through said slot, the head being wider than the width of the slot, a tubular handle connected to the supporting 40 plate, a guide means therein having an L-shaped slot with one arm extending longitudinally and the other transversely as to the axis of the handle, a pin on the stem extending into said slot, and means operatively connected to the handle and to 45 the stem to rotate the stem and to move the stem longitudinally.

12. In a safety razor, a supporting plate, a clamping plate having a pair of arms, a hinge connecting said arms to the supporting plate, 55 said hinge having a pintle with a fixed axis, means forming a slip connection between the arms and the pintle, means to rotate the pintle to swing the clamping plate from its open to a position parallel to the supporting plate, and means to move the clamping plate in a direction at right angles to the plane of the supporting plate to accommodate blades of varying thickness and to 60 positively clamp the blades between the supporting and the clamping plate, the means to rotate the pintle including a spring whereby the clamping plate may be turned on its hinge by hand and thereby compressing the spring, the said spring being operative to rotate the pintle and thus move the clamping plate from a position 65 parallel to the supporting plate to a position at right angles thereto.

AXEL S. CARLSON.
